UNITED STATES PATENT OFFICE.

GUSTAVE A. GALLOWITZ, OF NEW YORK, N. Y., ASSIGNOR TO THE KNY-SCHEERER CORPORATION OF AMERICA, OF NEW YORK, N. Y., A CORPORATION OF NEW YORK.

PHYSICIAN'S EXAMINING TABLE.

Application filed June 10, 1926. Serial No. 114,964.

This invention relates to an improvement in a physician's examining table and the novelty resides in the adaptation and arrangement of parts as will be more fully 5 hereinafter pointed out.

As the top of the table is at a height convenient for the physician so as to prevent the necessity of unusual bending or stooping during the examination it is essential that 10 there should be provided a step for the patient to enable the patient to mount the table in a convenient and easy manner. This step interferes with the proper use of the table by the physician after the patient is 15 mounted thereon unless it slides out of the way, but it must also be securely locked in its open position against possible slipping during its use by the patient. My device is adapted to solve these problems and does so 20 in an efficient and economical manner.

Referring to the drawings Figure 1 is a side view of my complete device. Figure 2 is a top plan view of the lower portion of the same on line 2—2 of Figure 1. Figure 3 is a 25 side view of a portion of Figure 2 on the line 3—3. Figure 4 is a perspective of the complete step.

In the drawings 10 is a base member having longitudinal bars 11 and a front cross 30 bar 12. A top 13 is mounted on a pair of rack bars 14 which pass through on either side a pair of gear boxes 14 rigidly mounted on base 10 and which are operated by means of a driving shaft 16 to which is rigidly secured a hand wheel 17 having a handle 18 all 35 of which is usual construction which permits of the usual raising and lowering of the top 13. A head member 19 is pivoted in the usual manner at 20 to the top 13 and under control of the usual manually 40 adjusted supporting bar 21 which can be raised and lowered as may be desired by means of the toothed ratchet 22 engaging over the cross bar 23 and a rod 24 serves as a guiding 45 rod to prevent said bar 21 from being thrown out of engaging position. A foot support member 25 is pivoted in the usual manner at 26 to the top 13 and by means of the usual ratchet bar 27 engaging cross bar 28 may 50 be adjusted to the desired position.

The foregoing construction is all well known and the operation of the same is in every way usual and the base frame 10 has a rear sloping pair of uprights 29 which 55 through their inward sloping at the upper

end permit the head portion 19 to be thrown to the lowermost position desired.

A pair of guideways 30 are rigidly secured to the inside of the longitudinal bars 11 being closed at their inner ends but 60 being supported at their open outer ends by cross plates 36. A step member 31 having a pair of legs 32 and castors 33 of usual construction on the lower ends of said legs and also having a bevelled lug 34 on each 65 side and an inset hook member 35 on each of the inner ends adapted to hook over the cross bar 12 is used with said base 10.

This step 31 may be entirely removed from the table but ordinarily will be placed 70 so that the bevelled lugs 34 will register in the pair of guideways 30 travelling back and forth therein as the step member 31 is pushed in and out rolling upon the castors 33. The inward movement of said step being limited by the engagement of the lugs 34 with the inner ends of the guideways 30 and the outer movement of said step to the full extended position bringing the bevelled 75 edges of said lugs 34 over said cross plates 36 whereby lugs 34 lock said step in the outward position and the hook members 35 prevent the step 31 from being pulled further as they engage the cross bar 12. It is thus seen that in this outward position of 80 this step 31 it is secured against accidental movement being locked between the hooks 35 engaging the cross bar 12 and the lugs 34 engaging the cross plate members 36.

In order to remove the step 31 from the 85 table so as to take it away it is then necessary to tilt the step 31 at its outer end until the lugs 34 are freed of the cross plates 36 and then pushing back unhook the hooks 35 from the cross bar 12 whereby the step 90 31 is freed so that it may be taken away. In ordinary usage the step will be left in the mounted position in the chair so that when it is desired to push the step 31 inwardly 95 from its locked position as described it is necessary to tilt the step upwardly at its outer end so that the lugs 34 will ride over the cross plates 36 and pushing in slightly the lugs will then register inside of the cross plates 36 and in the guideways 30 so 100 that the step may be pushed all the way into its closed position and out of the way of the physician using the said table. It is thus clear that the step 31 may be quickly 105 and easily slid back and forth and locked 110

in the full extended position or unlocked to be pushed out of the way in the encased or closed position.

I claim:

- 5 1. In a physician's examining table a slide-
able step the forward end of which rests upon
the floor, and means for locking it in its
extended position.
- 10 2. In a physician's examining table the
combination of slotted guideways rigidly
mounted on the inside of the horizontal
lower longitudinal bars of the base frame
of said table, a step having two legs mounted
on castors on the front thereof, two hooks
15 at the rear adapted to engage the front
cross bar of said table and a bevelled lug
on each side adapted to travel in said slot-
ted guideways and ride over and lock
against the outer ends of said guideways.
- 20 3. In a physician's examining table the
combination of a metallic base frame, a top
adjustable as to height having head and
foot portions pivoted thereto and adjustable
at their outer ends, slotted guideways rigid-

ly mounted on the inside of the horizontal 25
lower longitudinal bars of the base frame
of said table, a step having two legs mounted
on castors on the front thereof, two
hooks at the rear adapted to engage the
front cross bar of said table and a bevelled 30
lug on each side adapted to travel in said
slotted guideways and ride over and lock
against the outer ends of said guideways.

4. In a physician's examining table a slide-
able step and means for locking it in its ex-
tended position comprising hook members
35 on the rear of said step adapted to engage
the front lower cross bar of the base frame
of said table, slotted guideways rigidly
mounted on the inside of the horizontal 40
lower longitudinal bars of said base frame
and a bevelled lug on each side adapted to
travel in said slotted guideways and ride
over and lock against the outer ends of said
45 guideways.

In testimony whereof I affix my signature.

GUSTAVE A. GALLOWITZ.
